UNITED STATES PATENT OFFICE.

THOMAS MILLARD NICHOLS, OF ASHLAND, KENTUCKY.

CRANE.

1,307,412.

Specification of Letters Patent. Patented June 24, 1919.

Application filed December 21, 1917. Serial No. 208,262.

To all whom it may concern:

Be it known that I, THOMAS M. NICHOLS, a citizen of the United States, residing at Ashland, in the county of Boyd and State 5 of Kentucky, have invented a new and useful Crane, of which the following is a specification.

The device forming the subject matter of this application is a crane, and one object 10 of the invention is to provide novel means whereby a truck carrying the working parts of the structure may be propelled, means being provided whereby a turn table may be rotated, means being supplied whereby a 15 grab may be raised, lowered and dumped, the raising and lowering means being regulated by a brake, all of the instrumentalities aforesaid being simple and expeditiously controlled, a single motor being effective to operate the various movable parts of 20 the structure.

A further object of the invention is to improve generally and to enhance the utility of devices of that type to which the present 25 invention appertains.

With the above and other objects in view which will appear as the description proceeds, the invention resides in the combination and arrangement of parts and in the details of construction hereinafter described 30 and claimed, it being understood that changes in the precise embodiment of the invention herein disclosed, can be made within the scope of what is claimed, without departing 35 from the spirit of the invention.

In the accompanying drawings:

Figure 1 shows in side elevation, a device 40 constructed in accordance with the present invention;

Fig. 2 is an elevation disclosing the opposite side of the device from that delineated in Fig. 1, parts being broken away;

Fig. 3 is a top plan of the complete crane;

Fig. 4 is a transverse section taken approximately on the line 4—4 of Fig. 3;

Fig. 5 is a fragmental rear elevation showing a portion of the turn table and parts carried thereby;

Fig. 6 is an elevation disclosing a clamping device whereby one of the operating lines is held at times;

Fig. 7 is an elevation of the load grab; and

Fig. 8 is a diagram showing the circuits.

In carrying out the present invention, 55 there is provided a truck frame 1 on which is journaled a driving axle 2 provided with wheels 3 adapted to traverse rails 4. An axle 5 is journaled on the truck frame 1 and carries wheels 6 coöperating with the rails 60 4. The truck comprises a platform 7 to which is secured a base plate 8 carrying a rack 9, the teeth of which are vertically disposed. The periphery of the base plate 8, about the rack 9, forms a track 10. The 65 base plate 8 which, in substance, constitutes a part of the truck, has a bearing 11 extending downwardly through the platform 7.

The numeral 12 marks a turn table having a bearing 14 coacting with the bearing 70 11 of the base plate 8. Wheels 15 are journaled on the turn table 12 and engage the track portion 10 of the base plate 8.

A tubular shaft 16 is journaled in the bearing 14 of the turn table 12 and in the 75 bearing 11 of the base plate 8 and retains the turn table against lateral movement with respect to the base plate. The shaft 16 is supported by a beveled pinion 17 secured to the shaft and resting on the bearing 14. 80 A beveled pinion 18 is secured to the lower end of the tubular shaft 16 and meshes into a beveled pinion 19 carried by a horizontal shaft 20 journaled in hangers 21 on the truck frame 1. The shaft 20 supports a 85 sprocket wheel 22 about which is trained a sprocket chain 23 coacting with a sprocket wheel 24 on the axle 2 of the truck. A brake lever 25, under the control of an operator, is fulcrumed on the turn table 12 and 90 like other operating levers to be mentioned hereinafter, is disposed in accessible relation to a seat 28 mounted on the rear end of the turn table 12. The lever 25 is supplied with a latch mechanism 26 adapted to 95 coöperate with a segment 27 on the turn table 12. One end of a flexible element 29 is made fast to the lever 25, the flexible element extending across a sheave 30 journaled on a support 31 carried by a turn table 12. 100 From the sheave 30, the flexible element 29 extends downwardly through the tubular

shaft 16 and is connected with one end of a bell crank lever 32 fulcrumed at 33 on the truck frame 1. A connection 34 is attached to the other end of the bell crank lever 32 and leads to a brake beam 35, pivotally supported as shown at 36 upon the truck frame 1, the brake beam carrying shoes 37 coöperating with the truck wheels 6.

Bearings 42 are erected on the turn table 12, and a shaft 43 is journaled in the bearings and is slideable longitudinally therein. The outer end of the shaft 43 carries a beveled friction wheel 44 coöperating with a beveled friction wheel 45 secured to a vertical shaft 46 journaled in a bearing 47 carried by the turn table 12. A pinion 48 is carried by the lower end of the shaft 46 and meshes into the rack 9 of the base plate 8. A beveled pinion 51 is secured at 50 to the shaft 43 and is adapted to mesh into the beveled pinion 17 which is secured to the upper end of the vertical shaft 16. The hub of the pinion 51 is provided with a shift collar 52, to which a rearwardly extended lever 53 is pivoted as indicated at 54. The forward end of the lever 53 is fulcrumed on a standard 55 carried by the turn table 12, the lever being supplied with a latch mechanism 56, coacting with a keeper 57 carried by the turn table 12.

A gear wheel 58 is secured to the shaft 43 and meshes into a pinion 59 constituting a part of a reversible electric motor 60 carried by the turn table 12. The pinion 59 of the motor 60 meshes into a gear wheel 61 constituting a part of a drum 64 carried by a horizontal shaft 62 journaled in bearings 63 on the turn table 12. The drum 64 is splined at 65 to the shaft 62, so that the drum may be adjusted longitudinally of the shaft, the spline constituting means for coupling the drum and the shaft together for simultaneous rotation. The numeral 66 designates a rearwardly extended lever fulcrumed on a standard 67 carried by the turn table, and provided with a latch mechanism 68 coacting with a keeper 69 on the turn table, the lever constituting means for shifting the drum 64 endwise.

50 A brake disk 70 is mounted on one end of the shaft 62 and is engaged by a strap 71, the ends of which are pivoted to the forwardly presented arms 72 of a forked lever 73, fulcrumed intermediate its ends on a bracket 74 mounted on a solenoid magnet 75 carried by the turn table 12. The rear end of the lever 73 is pivoted at 76 to the movable core 77 of the magnet 75, the core being provided with a head 78, and there being a compression spring 79 surrounding a portion of the core, one end of the spring abutting against one end of the magnet and the other end of the spring abutting against the head 78, the function of the spring being

to tilt the lever 73 and to apply the strap 71 to the brake disk 70 when the magnet 75 is deenergized.

A lever 80 is disposed beneath the turn table 12 and is fulcrumed intermediate its ends thereon as shown at 81, one end of the lever being pivotally connected as shown at 82, with the lower end of the core 77 of the magnet 75. To the other end of the lever 80 a vertical actuating rod 83 is pivoted, the same extending slidably through the turn table 12 and being accessible to a person occupying the seat 28.

The numeral 85 designates a rheostat, and a controller is shown at 86, these members being mounted on the turn table 12. Line 80 conductors 87 are shown, the same representing any suitable source of electric energy. The numeral 88 designates a circuit connected with the conductors 87 and including the rheostat 85, the motor 60 and the controller 86. At 89 there appears an auxiliary circuit including a switch member 90, and a switch member 91, the latter element being carried by the lever 66 and being movable therewith toward and away from the switch member 90, so as to open and close the auxiliary circuit 89. The auxiliary circuit 89 includes a controller 86 and the solenoid magnet 75.

The invention comprises a forwardly presented inclined boom 38 mounted at 39 on the turn table 12 and supported by guys 40, the rear ends of which are attached to the turn table as shown at 41. A clamp is mounted on the boom 38 near to the upper end thereof, and includes a fixed jaw 92 attached to the boom, and having an upstanding rear end 93. A movable jaw 94 is disposed above the fixed jaw 92 and is adapted to coact therewith, the movable jaw being connected to the fixed jaw by means of pivotally mounted links 95. A retractile spring 96 extends between the end 93 of the fixed jaw 92 and the movable jaw 94, and serves to retract the movable jaw out of gripping relation with respect to the fixed jaw. A flexible element 97 is attached to the forward end of the movable jaw 94 and is extended around a sheave 98 on the boom 38. From the sheave 98, the flexible element 97 is extended downwardly and rearwardly beneath an idler 99, which as shown in Fig. 3, may be carried by the connection 39 which unites the boom 38 to the turn table 12. From the idler 99, the flexible element 97 is carried rearwardly and is secured to a lever 100 fulcrumed on the turn table and provided with a latch mechanism 101 adapted to coact with a segment 102 which is also mounted on the turn table.

The numeral 111 denotes a hoisting line trained over a sheave 112 on the boom 38, the rear end of the hoisting line 111 being

engaged as shown at 114 around the drum 64. From the sheave 112 the hoisting line 111 extends downwardly to crotch lines 106 connected with the upper ends of levers 107, disposed in pairs, the levers of each pair being united, intermediate their ends, by means of a pivotal connection 108. The levers 107 are provided at their lower ends, with jaws 109. A rider 110 is mounted to 10 reciprocate vertically on the levers 107, below the pivotal connections 108. When the rider 110 is in a depressed position, the levers 107 are prevented from swinging on their pivotal connections 108, and the jaws 109 are prevented from opening. When, however, the rider 110 is raised, then the levers 107 may swing apart on the pivotal connections 108, thereby permitting the jaws 109 to drop their load. The rider 110 is 20 connected to the lower end of a dump line 103, trained across a sheave 105 on the boom 38, the dump line extending between the movable jaw 94 of the clamp and the fixed jaw 92 thereof, the dump line being extended rearwardly through the end 93 of the fixed jaw 92 and being attached as indicated at 104 to the drum 64.

Let it be supposed that it is desired to 25 propel the truck 1—and in this connection it is to be understood that the specific means whereby the axle 2 is connected with the shaft 16 may be varied without jeopardizing the utility of the invention. The lever 66 is swung on its fulcrum 67 so as to move the drum 64 endwise, thereby placing the gear wheel 61 out of mesh with the pinion 59 of the motor 60. The shaft 43 is moved longitudinally by means of the lever 53 until the beveled pinion 51 on the sleeve is in 30 mesh with the beveled pinion 17 on the shaft 16. When the motor 60 is put into operation, the pinion 59 drives the gear wheel 58, the shaft 43 being rotated, and rotation being imparted to the beveled pinion 51. The beveled pinion 17 is driven from the beveled pinion 51, and the shaft 16 is rotated, the shaft 16 rotating the shaft 20 by means of the beveled pinions 18 and 19, the shaft 20 rotating the axle 2 and 35 wheels 3 by means of the sprocket wheel 22, the sprocket wheel 24 and the sprocket chain 23, or by any other equivalent mechanism. In this way, the truck 1 may be moved forwardly and rearwardly along the rails 4. When it is desired to apply the brakes to 40 the wheels 6, the lever 25 is manipulated, the flexible element 29 riding over the sheave 30 and moving longitudinally in the tubular shaft 16, the bell crank lever 32 being tilted on its fulcrum 38, and the connection 34 swinging the brake beam and the shoes 37, so that latter elements coöperate with the 45 wheels 6. The particular mechanism which is interposed between the lower end of the

flexible element 29 and the brake shoes 37 65 may be changed without materially impairing the utility of the machine, considered generally.

Let it be supposed that it is desired to 70 rotate the turn table 12. Then the shaft 43 is moved longitudinally by means of the lever 53 until the beveled pinion 51 is out of mesh with the beveled pinion 17, the friction wheel 44 being brought into engagement with the friction wheel 45. Motion is 75 now transmitted from the motor pinion 59 to the gear wheel 58, the shaft 43, the friction wheel 44, the friction wheel 45, the shaft 46 and the pinion 48, the latter element coacting with the rack 9 on the base plate 80 8 on the truck, to cause a rotation of the turn table 12, with the shaft 16 as an axis of rotation, the wheels 15 on the turn table 12 rolling in contact with the track portion 10 of the base plate 8.

The means whereby the truck 1 is propelled, the means whereby the turn table 12 is rotated, and the means whereby the brakes 37 are applied, have been discussed, and the operation of the hoisting line 111 90 and the dump line 103 will now be dealt with.

The shaft 43 is moved endwise by means of the lever 53 until the friction wheel 44 is out of engagement with the friction wheel 95 45 and until the beveled pinion 51 is out of mesh with the beveled pinion 17 on the shaft 16, the parts being shown in these positions in Fig. 4.

The drum 64 is moved endwise on the 10 shaft 62 by the lever 66, until the gear wheel 61 on the drum is in mesh with the motor pinion 59. The lever 66 carries the switch member 91 into engagement with the switch member 90, the circuit 89 being closed exteriorly of the controller 86. When the controller 86 is manipulated, current flows through the circuit 89 and energizes the magnet 75, the core 77 moving, responsive to the magnet 75, and overcoming the action of 110 the spring 79, the function of which is to keep the brake strap 71 normally applied to the disk 70. When the action of the spring 79 is overcome as aforesaid, the lever 73 is tilted, and the hold of the brake strap 115 71 on the disk 70 is released, the shaft 62 and the drum 64 being set free for rotation. By the aforesaid manipulation of the controller 86, the circuit 88 is closed and the motor 60 is energized, the pinion 59 and 120 the gear wheel 61 imparting rotation to the drum 64 and reeling in hoisting line 111 and the dump line 103. As soon as the circuits 88 and 89 are opened by a proper manipulation of the controller 86, the motor 60 125 stops, the shaft 62 and the drum 64 no longer are rotated, the magnet 75 is deenergized, the spring 79 reasserts itself, and the lever

76 applies the brake strap 71 to the disk 70 on the shaft 62, thus holding the load elevated. In order to lower the load, the lever 80 may be tilted by means of the actuating rod 83, the core 77 of the magnet 75 being drawn downwardly, against the action of the spring 79, the lever 73 being tilted on its fulcrum 74, and the hold of the brake strap 61 on the disk 70 being released.

10 From the foregoing it will be obvious that since the motor 60 is reversible, the hoisting line 111 and the dump line 103 may be reeled on the drum 64 and may be paid off the drum, the levers 107 and the load carried 15 by the jaws 109 being raised and lowered, as occasion may demand.

Let it be supposed that it is desired to dump the load which is carried by the jaws 109. The spring 96 draws the movable jaw 94 rearwardly, so that the dump line 103 is not normally gripped between the jaws 92 and 94. The operator manipulates the lever 100, thereby drawing the flexible element 97 rearwardly over the sheave 98, the upper end 25 of the flexible element moving forwardly toward the sheave 98, thereby drawing the movable jaw 94 downwardly and forwardly so that the dump line 103 is gripped between the jaws 92 and 94, the spring 96 being put 30 under tension, and the links 95 permitting the movable jaw 94 to have the necessary movement with respect to the fixed jaw 92. This operation holds the dump line 103. The drum 64 may now be rotated by means of 35 the pinion 59 and the gear wheel 61, to pay the hoisting line 111 off the drum to a slight extent, the hoisting line running out a trifle over the sheave 112, and permitting the levers 107 and the jaws 109 of the grip to 40 move downwardly. Since the dump line 103, being held between the jaws 92 and 94, does not participate in this downward movement, the rider 110 will not move downwardly the lower ends of the lever 107 sliding 45 downwardly through the rider and permitting a separation of the jaws 109, thereby dumping the load. As soon as the lever 100 is operated to release the flexible element 97, the spring 96 reacts on the movable jaw 94 50 and draws the same rearwardly, the dump line 103 being set free.

What is claimed is:—

1. In a crane, a truck; a propelling means on the truck; a turn table journaled on the 55 truck; means for rotating the turn table; a reversible motor on the turn table; mechanism continuously driven by the motor and bodily movable alternatively into and out of engagement with the means for rotating the 60 turn table, and into and out of engagement with the propelling means; and a winding means on the turn table, the winding means including a part movable into and out of coöperative relation to the motor.

2. In a crane, a truck; a turn table journaled on the truck; means for rotating the turn table; a reversible electric motor on the turn table; a propelling means on the truck; driven means coöperating with the motor and shiftable to coact at different times with the propelling means and with the means for rotating the turn table; a winding device on the turn table and comprising relatively movable members, one of which is movable into and out of coöperative relation to the 75 motor; mechanism under the control of an operator for moving said member into and out of coöperative relation to the motor; a brake controlling the other member of the winding device; a motor circuit; means in 80 the circuit for operating the brake; and a switch in the circuit, operated by said mechanism.

3. In a device of the class described, a support; a boom carried by the support; a winding device on the support; a grab; a releasing device controlling the grab; a clamp on the boom; a hoisting line trained across the boom and connected to the grab and to the winding device, the hoisting line 85 being independent of the clamp; a dump line controlled by the clamp and trained across the boom, the dump line being connected to the releasing device and to the winding device; and means under the control of an operator for manipulating the 90 clamp.

4. In a device of the class described, a support; a boom carried by the support; a winding device on the support; a grab; a releasing device controlling the grab; a clamp on the boom, and including a movable member; a hoisting line trained across the boom and connected to the grab and to the winding device, the hoisting line being independent 100 of the clamp; a dump line within the control of the movable member of the clamp and trained across the boom, the dump line being connected to the releasing device and to the winding device; yieldable means for 105 moving the movable member of the clamp in one direction, to release the dump line; and means under the control of an operator and connected with the movable member of the 110 clamp for moving the same in an opposite direction, to cause the movable member of the 115 clamp to engage the dump line.

5. In a device of the class described, a support; a boom carried by the support; a winding device on the support; a grab; a releasing device controlling the grab; a clamp on the boom and including a movable member; a hoisting line trained across the boom and connected to the grab and to the winding device, the hoisting line being independent of the clamp; a dump line 120 under the control of the movable member of the clamp and trained across the boom, 125

- the dump line being connected to the releasing device and to the winding device; a spring connected with the movable member of the clamp and constituting means for 5 retracting the movable member of the clamp to release the dump line; a flexible element connected at one end to the forward end of the movable member of the clamp, the flexible element being extended forwardly 10 around the boom and rearwardly to the support; and means on the support and connected with the flexible element, for draw-

ing the flexible element rearwardly, thereby to advance the movable member of the clamp and to cause the movable member of the 15 clamp to grip the dump line.

In testimony that I claim the foregoing as my own I have hereto affixed my signature in the presence of two witnesses.

THOMAS MILLARD NICHOLS.
